CONNECTICUT

LOG-IMPREGNATING MACHINE

Application filed October 22, 1928. Serial No. 314,294.

This invention relates to wood impregnating devices and in particular to a new impregnating machine which is adaptable for use in connection with logs.

5 A particular object of the invention is to provide a compact unit which may be moved from place to place and which is arranged to receive the end of a log which is to be impregnated throughout its length with a pre-
10 serving or coloring liquid.

A further object of the invention is to provide a log impregnating mechanism which will be mounted upon a chassis and which may be moved vertically so that a
15 minimum of handling of the logs will be necessary in treatment thereof.

20 A further object of the invention is to arrange upon a suitable chassis, the entire operating plant and to mount upon a movable table, a log holding clamp and hood so that logs, regardless of size, may be quickly and efficiently operated upon.

In our improved machine, we have eliminated one of the steps heretofore used in the
25 impregnation of a log, that is, the forcing of air through the log in order to force the sap out. We have found that by forcing the liquid under high pressure into the hood and automatically exhausting the air from the
30 hood so that the entire pressure of the liquid therein may be evenly distributed over the blunt end of the log that the entire log will be impregnated from bark to bark and the sap will be forced out ahead of the impregnating liquid.

To enable others skilled in the art to fully comprehend the underlying features of our invention that they may embody the same in the various modifications in structure and
40 relation contemplated, a drawing depicting a preferred form has been annexed as a part of this disclosure and in such drawing, similar reference characters denote corresponding parts throughout all the views, of which,

45 Figure 1 is a view in top plan illustrating the lay-out of our improved log impregnating unit, the view showing the liquid handling mechanism on one end and the log hanlding mechanism on the other end.

50 Figure 2 is a view in side elevation of the

unit illustrated in Figure 1, parts thereof being broken away to show the interior construction.

Figure 3 is a front view in elevation of the clamp frame illustrating how the clamps
55 are mounted at the proper angle to effectively grip the log so that the same may be drawn into the hood.

Figure 4 is an enlarged detail in section, taken through one corner of the clamp frame
60 and indicated by the lines 4-4 of Figure 3.

Referring to the drawings in detail, 5 indicates the chassis upon which the entire unit is mounted, this chassis being made of sheet steel preferably and flanged at its outer edges, the chassis being supported at spaced relation with the ground through the medium of the swivelled castor 6, one of which is provided at each corner of the chassis. This chassis supports, through the medium
65 of the table guide 7, the table 8 which is made substantially the same as the chassis in that it is a steel plate having flanged edges and adjacent the four corners thereof, it has secured thereto the depending pipes 9 which telescope into the outer pipes 10 supported on the chassis 5, both of the pipes constituting the table guides 9 hereinbefore referred to. It is quite evident that through the use of these table guides, the table may have free vertical movement relatively to the chassis and in order to carry out this feature, the center plate 11 is secured to the under side of the table at its center and supports a depending
70 jack screw 12 which passes through a threaded bushing 13 which has a forced fit within the sleeve 14. This sleeve 14 forms a hub for the center of the jack ring 15 which ring consists of a peripheral flange band 16 joined as by welding or otherwise to the sleeve 14 and to the ring 16, this construction providing a ring which may be revolved and carry with it not only the sleeve 14 but also the bushing 13, the bushing resting upon the chassis 5 and consequently forcing the
75 jack screw 12 upwardly or downwardly therein depending upon which direction the jack ring 15 is revolved. This movement of the jack screw raises and lowers the table in order that the working parts of the impreg-

80

100

nator may be brought into alignment with the end of a log denoted by the numeral 18 which has been brought up adjacent the unit on a suitable cradle or truck.

5 The table 8 supports at one end, a casting 19 in which is formed a cone-shaped hood 20. This cone-shaped hood is provided with an edge flange 21 which bounds a log receiving opening in the hood, it being understood that 10 the end of the log will be chamfered in order that it will be self-seating within the hood 20. In this way a variety of logs of different diameters may be accommodated without the necessity of changing the hood and it is quite 15 evident that the lesser the angle of the inner wall of the hood, the less will be the weight, due to the cutting of the end of the log to fit therein. Also, the less chamfer necessary on the end of the log, the greater will be the 20 area of impregnation which is very desirable.

The inside of the hood is finished smoothly so that a liquid tight joint is made between the wall of the hood and the chamfer of the 25 log when the latter has been drawn thereinto through the medium of the clamp. The hood 20 is provided in its rear wall with a series of openings one of which is arranged to accommodate an air vent pipe 22 which is held in the rear wall of the hood in a suitable stuffing 30 box 23, it being understood that loosening of the stuffing box nut 24 will permit withdrawal or insertion of the pipe 22, depending upon the size of log occupying the hood. A suitable vent valve 25 is provided in the end 35 of the pipe 22 so that as the liquid fills the hood, the air will be vented and it will be possible for the entire space between the hood and the log to be completely filled with the impregnating liquid.

40 Another stuffing box in the end of the hood indicated by the numeral 26 accommodates a fluid drain pipe 27 through the medium of which any liquid left in the hood after the impregnating process has been completed may 45 be siphoned into the reservoir 28 in addition to the two stuffing boxes. The hood end is provided with an inlet pipe 29 which is connected by the flexible hose 30 to the compression tank 31, this flexible hose 30 being necessary in order to permit adjustment of the 50 hood vertically. The pressure tank 31 is supplied by the pipe 32 which conveys the impregnating liquid from the pump 33. This pump 33 is provided with a pump handle 34 and is of any well-known commercial type. If desired, this pump may be also operated by electric power but it is sufficient to note that it is so situated that it will throw off the 55 liquid from the reservoir 28 through the pipe 35 and force it into the pressure chamber 31 which is provided with a suitable pressure slot 36 and gauge glass 37, the pressure being suitably built up in this tank 31 and being supplied to the hood as desired through the 60 medium of the valve 38 which is carried at

the outer end of the pipe 29. Suitable valves 39 and 25 may be employed in the pipes 27 and 22 respectively for controlling the outlets therefrom and also to close the same when the liquid pressure is applied inside the hood 70 during an impregnating process.

The hood member or casting 19 is provided in its flange 21 with a plurality of openings through which pass the clamp rods 40, the ends thereof being threaded to receive suitable adjusting nuts 41 through the medium of which longitudinal movement of the rods 40 is accomplished in order to draw the hooks 42 tightly into the wood of the log so that the same will be drawn in turn into the hood 20. These hooks 42 are made from spaced hook plates 43 which are joined by the rivets 44 and are pivoted on the pin 45 in suitable brackets 46 secured in the clamp frame 47. These brackets 46 are disposed at the corners of the clamp frame so that the hooks will swing toward the center of the frame and consequently will be self-adjusting to any size log placed into the frame. The brackets 46 are riveted or otherwise secured in the frame 47 which is in turn, through the medium of the angle members 48, secured in position at the front of the table 8.

In operating our improved device, it is simply necessary to bring the log up to a point adjacent the frame 47 and pass the chamfered end thereof through the frame and into the hood after the same has been adjusted through the medium of the jack ring and jack screw to the proper height. When the log has been placed into the hood, the hooks 42 are drawn upon by the rods 40 which are adjusted by the turning of the nut 41 on the threaded end thereof, so that the hooks are drawn tightly into the log surface and continued tightening up on the nuts 41 will draw the log into the hood and will practically seal its chamfered edge against the interior surface of the hood. After this has been accomplished, the air valves 25 in the vent pipes 22 are opened and the pumping operation commenced, the liquid being drawn from the reservoir 28 and being either an impregnating liquid or a coloring chemical and which, after passing through the pump 33, passes into the chamber 31 in which a sufficient pressure has been built up to further force the liquid through the pipe 30 into the hood. This liquid forced in will, of course, imprison the air in the upper part of the hood chamber but this air will be vented through the pipe 22 and as soon as all of the air has been expelled, the valve 25 will be closed and the impregnating process will be completed. The closing of the valve 38 will then prevent any admission of liquid from the pressure tank into the hood and the remaining liquid in the hood compartment will be drawn off through the outlet pipe 27 and back into the reservoir 28. After this has been completed, the nuts 41 on the rods 40 130

will be loosened up so that the hooks 42 may be removed from the log and the log itself taken out of the hood and removed from the frame.

It is quite evident that with a construction 5 of this character, the impregnation of logs may be quickly and efficiently carried out and the impregnating process may be carried on in a very satisfactory manner due to the fact that no forcing out of the sap as an additional 10 step in the process need be accomplished.

It is also evident that in a machine of this character that is mounted on a suitable chassis, that the impregnating hood and log holding frame may be adjusted to the proper 15 height to receive a log of any size, thus making handling of the log unnecessary and in this way, saving the time of the operator.

It is evident that an individual can handle the entire process and apparatus without assistance as the power exerted by the jack screw will be ample to raise the table and hood and frame supported thereon.

While we have illustrated and described our invention with some degree of particularity, we realize that in practice various alterations therein may be made. We therefore reserve the right and privilege of changing the form of the details of construction or otherwise altering the arrangement of the correlated parts without departing from the spirit 30 of the invention or the scope of the appended claims.

Having thus described our invention what we claim as new and desire to secure by 35 United States Letters Patent is:—

1. A log impregnating machine comprising a mobile chassis, a table thereon, means for raising and lowering said table, a hood carried by the table into which one end of a 40 log to be impregnated is placed and means for forcing a liquid into said hood.

2. A log impregnating machine comprising a mobile chassis, a table thereon, means for raising and lowering said table, a hood carried by the table into which one end of a 45 log to be impregnated is placed and means for drawing the log end into the hood forcibly.

3. In a log impregnating machine, a hood into which the log end is placed, means for 50 forcing liquid into the hood, an air vent pipe in the hood and a liquid drain pipe in the hood, both of said pipes being adjustable relatively to the log end.

4. A log impregnating machine comprising a mobile chassis, a table thereon, means for raising and lowering said table, a hood carried by the table into which one end of a 55 log to be impregnated is placed and means for forcing the liquid into said hood and 60 means for drawing the log end into the hood forcibly.

5. A log impregnating machine comprising a mobile chassis, a table thereon, means for raising and lowering said table, a hood carried by the table into which one end of a 65

log to be impregnated is placed, means for introducing a liquid into the hood under pressure, said means including a pump and pressure tank mounted upon said chassis and a clamp holding frame mounted on the table and arranged to engage said log to draw the 70 end thereof into the hood forcibly.

6. A log impregnating machine comprising a mobile chassis, a table mounted thereon, telescopic guide members connecting the table and the chassis, a jack screw secured to the under side of said table, a jack ring for moving the screw vertically whereby the table may be raised and lowered and a pressure hood carried on the table into which one end 75 of a log to be impregnated is placed.

7. A log impregnating machine comprising a mobile chassis, a table, guide members supporting the table on said chassis, a jack screw secured to the table, a jack ring mounted for 80 revolving movement on said chassis and arranged to operate the jack screw to cause raising and lowering of said table, a frame at one side of the table, a hood at the opposite side of the table into which one end of a log to be 85 impregnated is placed, the log passing through said frame, means for forcing a liquid into said hood whereby the log will be impregnated throughout its length and a plurality of hook members carried by said 90 frame and means for drawing upon said hook members whereby the log end will be forcibly secured within said hood.

In testimony whereof we affix our signatures.
